PROOF PRESS PAPER GRIPPER

Freeman Barney, Spring Lake, Mich., assignor to
 The Challenge Machinery Company, Grand
 Haven, Mich., a corporation of Michigan

Application December 13, 1948, Serial No. 64,934

4 Claims. (Cl. 101—277)

1

This invention relates to improvements in connection with the paper grippers of proof printing presses.

Printing presses for printing proof sheets, which may be examined for errors and the correction of them before final printing takes place, are used in many printing establishments and particularly for newspapers. The printing of the proof sheets is by gripping an edge of the sheet on a horizontally mounted rotatable printing drum, rotating the drum usually by manual operation, and connecting the drum with a horizontally movable bed upon which the printing form is carried, the bed being movable underneath the rotating drum so that the imprint of inked type is made on the paper sheet. The drum is rotated reversely after the printing has taken place so as to return the bed to the position which it initially occupied, ready for the printing of a succeeding proof sheet.

The present invention is directed to novel improvements in gripping mechanism used with the printing cylinder or platen. An edge of a sheet of paper is brought to and located at a pre-selected position on the cylinder and the sheet gripped at such edge. Such gripping means, carried in the present invention, is automatically made inoperative when the bed reaches its innermost position and with the cylinder positioned so that the grippers, which immediately grasp the paper, are in inoperative position. They are automatically rendered operable to grip the paper approximately as soon as the succeeding printing operation starts. Furthermore, with my invention when, by reversing the turning movement of the printing cylinder, the bed is moved outwardly for a succeeding printing operation, the gripping mechanism which has been in its gripping position during such outward movement of the bed is automatically operated as the bed approaches its extreme outer position to release the grippers for the insertion of the edge of a sheet of paper, and thereafter quickly again made operative to grip the edge of the paper sheet. Thereupon the paper sheet, upon which the proof imprint is to be made, is ready to follow the printing cylinder upon reversing its movement for the succeeding printing operation.

A further feature of the invention and one of the objects to be attained thereby is concerned with novel locating stop means for the gripped edge of the sheet of paper, for properly locating it that it shall evenly wrap around the cylinder and not have its side edges disposed at an angle to the straight line of travel of the form carrying bed. A plurality of such stops are mounted on

2

the cylinder and each is independently adjustable to insure the proper edge position of the proof sheet to be printed, when it is connected by the gripping mechanism of my invention to the cylinder.

Other objects and purposes than those stated will be apparent and understood from the following description, taken in connection with the accompanying drawings, in which,

10 Fig. 1 is a side elevation of a proof printing press having my invention incorporated therein.

Fig. 2 is an end elevation with parts of the printing cylinder broken away and shown in section, for better disclosure of structure.

15 Fig. 3 is an enlarged horizontal section substantially on the plane of line 3—3 of Fig. 2, looking downwardly.

Fig. 4 is a like view showing the mechanism in another position when the gripping mechanism is momentarily released at the approach of the form carrying bed to its outer position.

20 Fig. 5 is a view like Fig. 4 with the parts in a still further position or that occupied by them when the form carrying bed has reached its outermost position, and the gripping mechanism returned to sheet gripping position.

Fig. 6 is a vertical section through the printing cylinder substantially on the plane of line 6—6 of Fig. 2, and,

25 Fig. 7 is an enlarged vertical section substantially on the plane of line 7—7 of Fig. 2, showing the structure of the adjustable paper edge stops.

Like reference characters refer to like parts in the different figures of the drawings.

30 In the construction of the proof press, a supporting structure is provided, including the horizontal table 1 supported at a desired height by ends 2 and with lower horizontal frame bars 3 between the ends. Substantially centrally of the table and at each side thereof a pair of spaced vertical guides 4 are permanently secured connected with the table 1 at their lower ends and extending above such table. A cross bar 5 may extend between and connect to each pair of

35 guides 4 at their upper ends. At what may be termed the rear end portion of the table, vertically positioned side supports 6 are located, extending upwardly a distance and carrying a generally horizontal feed table 7 on which a sheet of paper to be proof printed is located to be fed to the printing cylinder.

40 A journal 8 is slidably mounted between the guides 4 of each pair of guides. Each journal, through a vertical rod 9 pivotally connected to its lower end, is connected to an eccentric housing 10 around an eccentric 11. The two eccentrics 11,

one at each side of the machine, are carried on a horizontal shaft which may be rocked to raise and lower the journals 8 and the printing cylinder which is carried by them. Such cylinder raising and lowering mechanism forms no part of the present invention.

The printing cylinder includes a hollow cylindrical outer shell 12 with vertical ends 13 closing the shell. A gear 14 is permanently fastened at one end of the cylinder. A tubular shaft 15 passes axially through the cylinder and beyond each of the ends 13 and gear 14, passing through the journals 8 in which the shaft is rotatably mounted. The cylinder secured to the shaft is turned by a crank 16 fastened to one end of the shaft as shown in Fig. 2.

A rod 17 is slidably mounted lengthwise and within the shaft 15. At one end, that nearest the crank 16, it terminates short of the adjacent end of the tubular shaft 15 and between it and a plug threaded into such end of the shaft 15 a coiled compression spring 18 is located, which acts to move the rod 17 lengthwise of the shaft 15 to the right (Fig. 2), or what in practice will be to the rear side of the machine, the crank 16 being at the front side. Such shaft 17 extends beyond the rear end of the tubular shaft 15, as shown in Fig. 2. The rod 17 at spaced intervals in its length, is grooved with continuous annular grooves around it reducing the diameter of the rod 17 at the bottoms of the grooves as at 19 and with conical surfaces 20 from the bottoms of the grooves to the periphery of the rod, extending from the groove bottoms toward the back of the machine.

The cylinder shell 12 at one side, and between the ends 13 has a segment removed for its length leaving a relatively wide opening 21 as shown in Fig. 6. A bar 22 extends between the ends 13 adjacent the opening, to which one end of a covering member 23 or tympan is secured, leading therefrom around the outer side of the cylinder shell 12 to the other edge of the opening at 21 and turned inwardly therein. It is clamped in place by the outer bar 24 of the gripping mechanism about to be described, which bar is located lengthwise of the opening 21 at said opposite longitudinal edge thereof, its outer surface being substantially flush with the adjacent outer surface of the cylinder 12.

The gripping mechanism, in addition to the outer bar 24, includes a second and inner bar 25 parallel to the outer bar, the two bars being integrally connected together by spaced connecting legs 26 between them. A plurality of radially disposed rods 28, spaced from each other, pass freely through aligned openings in the bars 24 and 25 and at their inner ends through openings made in the hollow shaft 15. The inner ends of the rod 28 are adapted to enter the grooves in the rod 17. Gripper heads 29 having flat under surfaces are at the outer ends of rods 28 and normally, when free to do so, will bear against the outer side of the bar 24 under the influence of compression springs 30 around the rods. It is between the undersides of the gripping heads 29 and the outer side of the bar 24 that the edge of the sheet to be printed is gripped. Such gripping will occur whenever the inner ends of the rods 28 are at the bottoms of the annular grooves in the rod 17. But on movement of the rod 17 (Fig. 2) to the left, the inner ends of the radial rods 28 ride upon the conical surfaces 20, which act as cams to force said rods 28 and their heads 29 outwardly and separate the inner sides

of the heads 29 from the bar 24. This frame which carries the grippers is secured to the cylinder by headed set screws 27 passing through the legs 26 and screwed into thickened inner portions of the drum shell 12 as shown in Fig. 6.

The upper bar 24 has a plurality of spaced adjustable stops thereon. The bar 24 at places where said stops are located (Fig. 7) is drilled through from one side to the other and a pin or rod 31 secured in each of the drilled openings and extend beyond the bar 24 into the opening at 21 of the cylinder. The stop members 32, of a generally L-shape, each has an upper leg extending over bar 24 and a leg at right angles extending at the inner side of said bar 24. A coiled spring 33 around each pin 31 is between said bar 24 and each stop, the bar and stop being recessed for receiving the ends of the spring. Each rod 31 is threaded at its free end portion to receive a nut 34 by means of which the stop may be adjusted so that the free ends of the upper legs over the bar 24 are presented toward the feed table 7, and provide stops against which the edge of a paper sheet which is to be printed comes in moving said paper at said edge portions under the gripping heads 29 which, at the time, are lifted above the upper surface of the bar 24. It is evident that with the plurality of stops 32 each independently adjustable the proper location of a paper sheet which is to be printed may be obtained.

An elongated form holding bed 35 is located over the table 7, and is mounted to move back and forth thereon underneath the cylinder. At 35 one side a rack bar 36, the length of the bed is secured, the teeth at its upper edge being in mesh with the gear 14. Between the upwardly extending flanges at the side of the bed (Fig. 2) the form made up of type, cuts and the like is secured; and of course an inking mechanism, not shown in the present application, is located at the front of the cylinder over the bed for inking the type. With reference to Fig. 1, the movable bed is substantially at its middle position. With continued turning of the cylinder counter-clockwise, as indicated by the arrow, the bed is moved to the right and the bracket 37 at the outer end of the bed, and which in practice is permanently secured at the outer side of the rack bar 36, is brought to a mechanism for operating the grippers when it reaches such mechanism nearly at the end of the inward longitudinal movement of the bed during which printing takes place. The bracket 37 (Fig. 3) has an inclined edge extending from one end outwardly as indicated at 38, joining with a shorter edge 39 which parallels the length of the bed 35 and attached rack 36.

Near the opposite end of the rack 36, at the same outer side thereof, a finger 40 is pivotally mounted between its ends on a fixed support 41. It has an outer edge 42 which in the position shown at Fig. 3 is inclined to the length of the rack 36, and at its rear end a shorter edge 43 parallel to the rack 36. It may be held in the position shown in Fig. 3 by a movable keeper 44 therefor which, substantially of channel form (Figs. 4 and 5), is slidably mounted for a limited movement on a fixed block 45 connected with the rack. It is held in its keeper position normally by a compression spring 46 which moves it in a forward direction and when in such position is in the path of movement of the adjacent free end of the finger 40. But when moved against spring 46 to the position shown in Fig. 5,

it is out of the path of movement of the adjacent end of the finger 40 which may then be turned about its pivot to the position in Fig. 5. A bar 41 is secured to the back guide 4 of the pair of vertical guides at the rear side of the machine and at the inner side of said guide, at one end having a laterally turned ear or lug 48 which is in the path of movement of the keeper 44 when the bed is moved substantially to its outermost position, to the left in Fig. 1, the downwardly extending projection shown on the keeper 44 coming against the lug 48, whereupon keeper 44 is moved from the position in Fig. 4 to that shown in Fig. 5.

Spaced supporting brackets 49 are connected at the outer side of the rear vertical guides 4. Between their upper and lower ends a horizontal sleeve 50 is mounted for rocking movement on a rod extending between the brackets 49. An arm 51 at the middle of the sleeve 50 extends upwardly to bear against the adjacent rear end of the gripper actuating rod 17. Two other arms 52 one at each side of the arm 51 extend outwardly from the sleeve 50. A vertical bar 53, slotted at its upper end, engages a pin at the outer end of one of the arms 52. The bar 53 extends downwardly and has a pivotal connection at its lower end to a foot operated lever 54 pivotally mounted at 55 between its ends on the rear lower frame bar 3. Foot lever 54 extends to the front of the machine and at its front end has a foot pedal 56 which when it is pushed upon by foot pressure forces the arm 51 against the rear projecting end of the gripper actuating rod 17 moving it to compress spring 18 (Fig. 2), and lifting the gripper rods 28 and their heads 29 as the inclined conical surfaces 20 ride underneath the inner ends of the rods 28.

A second horizontal sleeve 57 is similarly mounted on and extends between the lower ends of brackets 49, spaced from and below sleeve 50. It has an arm 58 extending outwardly from it directly below the other upper arm 52. A link 59 is pivotally connected to said arm 52 at its upper end, and is slotted at its lower end to engage with a pin passing through the outer end portion of arm 58. Rocking the sleeve 57 in the same direction as sleeve 50 is rocked by the upward vertical movement of bar 53, causes the same longitudinal movement of the gripper actuating bar 17 with the same results taking place.

A second arm 60 is connected to the lower sleeve 57 and extends downwardly therefrom. A short rod 61 is mounted for horizontal sliding movement through a bracket support 62 therefor secured at the outer side of the front guide 4 of the back pair of guides. It has a pivotal connection with the arm 60 at its outer end. At its inner end it is provided with a roller 63 which, when the rod 61 occupies its normal position, is engaged by the inclined edge 33 of bracket 37 when the bed 35 approaches its rear or innermost position of movement. That is, when the cylinder 12 has been turned counter-clockwise (Fig. 1) upon bracket 37 reaching the roller 63 on rod 60, the roller rides the inclined edge at 38 and rod 61 is moved outwardly until the shorter edge 39 is reached by such roller. Such edge at 39 is reached at the final completion of the rear movement of the bed. On stopping the turning of the drum, which will occur through appropriate stop means therefor, at such position rod 61 is held as shown in Fig. 3, and the gripping heads 29 are held in the upper positions to which they have been moved, with their lower sides

spaced from the upper side of the cooperating gripping bar 24 between which heads and bar the paper sheet has been gripped.

Similarly when the bed 35 is moved outwardly on reverse turning movement of the cylinder, the finger 42 comes to the roller 63 (Fig. 4) which rides the inclined edge 42, moving the rod 61 to the rear, with a release or elevation of the gripping heads 29. But when the bed 35 reaches its outermost position in which the roller 63 will have been moved to the edge 43 on finger 40 (Fig. 5), lug 48 moves the keeper 44 which has been in the path of movement of the end of finger 40 to the position shown in Fig. 5, releasing the finger, whereupon under the force of spring 18 the rod 61 will move the finger 42 to the position shown in Fig. 5 and the gripping heads 29 of rods 28 will return to their gripping position.

In the operation, with the bed 35 and attached rack 36 at outermost position, the edge of a paper sheet at the upper side of the feed table 7 is gripped by the gripping heads 29 against bar 24, which at such position of the cylinder and table is located at the upper side of the cylinder substantially as in Fig. 6. Turning the crank 16 to rotate the cylinder clockwise (Fig. 6) causes the paper sheet to follow the cylinder and wrap against it. On reaching the form carried by the bed after a partial revolution of the cylinder, the printing begins and continues until the outer end of the form has been reached and passed by. Upon continuing the rotation, the bracket at 37 reaches the roller 63 on rod 61 riding the inclined edge 38 to release the gripper heads 29 which are approximately under the feed table 7. At the same time, as shown in a copending application filed by me of even date, Ser. No. 64,933, the cylinder is lifted bodily a short distance. Thus on reverse movement of the cylinder, by turning the crank 16 in the opposite direction, no pressing of the cylinder against the type if the sheet has been removed occurs, and the proof sheet with the printing thereon may be removed as it has been released from all connection to the cylinder and is not pressed by the cylinder against the type form.

As soon as the reverse turning movement of the cylinder has taken place for a short time, so that the bracket 37 has moved away from the roller 63 which it has engaged, the gripping heads 29 are returned to initial position to press against the outer side of the bar 24. As the bed 35 approaches its outer position, roller 63 is engaged by the inclined edge 42 of the finger 40 which is held in a fixed position by the keeper at 44. This moves the gripping heads 29 outwardly to space their under flat sides from the adjacent side of bar 24, at a position in which said bar 24 is ahead of the position shown in Fig. 6, or to the right thereof, a short distance. The succeeding paper sheet on the table 7 has been moved at its edge portion where it is to be gripped farther than it will be located when the gripping takes place. Thereupon, when the cylinder 12 has been returned fully to its initial position, shown in Fig. 6 and the bed 35 is at its outermost position, the free edge of the paper sheet will have been reached by the locating stops 32 and the edge of the paper comes underneath the raised gripping heads 29. The paper sheet may be moved back by the moving stop 32. Such edge of the paper will be properly positioned such that at the full completion of the reverse turning movement of the cylinder, and the disengaging movement of the keeper 44, from the position in Fig. 4 to that

in Fig. 5 caused, as previously described, by the lug 43 engaging with the keeper, as in Fig. 5, the automatic return of the gripping heads to their operative position grips the succeeding sheet which is to be printed with it properly positioned and located with reference to the cylinder.

A foot operated release of the gripping heads 29 may be had at any time by pressing downward on the foot pedal 56. This may be needed at times in the operation of the proof press; or it may 10 occur in connection with short proof sheets.

The structure described is very practical and useful and is very satisfactory in practical use. The invention is defined in the appended claims and is to be considered comprehensive of all forms 15 of structure coming within their scope.

I claim:

1. In a structure as described, a horizontal cylinder, a hollow shaft extending therethrough, supports for said shaft in which the shaft is rotatably mounted, a horizontal bed located underneath the cylinder, a horizontal table supporting said bed and over which it is longitudinally movable, means for moving the bed back and forth on rotation of the cylinder in opposite directions, a rod axially located within said hollow shaft, said rod at one end extending beyond the adjacent end of the shaft, brackets supported by said table in fixed position, one at each side of the projecting end of said shaft carried rod, a bell crank lever structure mounted on said bracket having an arm engaging against the adjacent end of said rod, said rod within the shaft having a plurality of angular grooves therearound, one side of each groove being of conical form, a gripping bar secured to said cylinder longitudinally and at one side thereof having its outer surface substantially flush with the surface of said cylinder, a plurality of headed rods spaced from each other passing radially of the cylinder through said bar and through a side of said hollow shaft, their inner ends being received in the grooves of said rod within the shaft, each of said rods at its outer end having a head with a flat under-surface, a spring on each rod yieldingly moving said rod radially inward, means for moving said bell crank lever in a direction to move said rod within the shaft longitudinally, to cause the conical sides of the grooves to engage the inner ends of said radially disposed rods and move them outwardly against their springs, and projecting means carried adjacent each end of said bed at one side thereof, combined with means located in the path of movement of said projecting means on the bed for turning said bell crank lever to move said axially disposed rod lengthwise of said hollow shaft when said bed has moved longitudinally to its innermost position and has moved toward but a short distance short of its outermost position.

2. A structure as defined in claim 1, said means for actuating said bell crank lever, comprising a horizontal slidably movable rod connected at its other end with the other arm of said bell crank lever, and at its inner end located in the path of movement of said projecting members carried by the bed, each of said projecting members having inclined outer edges engaging with the inner end of said slidably mounted rod to move said rod outwardly by cam action when said projecting members reach the inner end of said rod and move with said bed by the rod.

3. A proof printing press comprising, a horizontal rotatable cylinder, a paper gripper at the periphery of the cylinder, a horizontal type bed 75

mounted for reciprocation under the cylinder, means for positively reciprocating said bed in either direction upon rotation of said cylinder, said bed having a printing movement and a return movement, a movable member acting to release said paper gripper, a cam member on said bed engageable with said movable member and acting to release the paper gripper at the end of the printing movement, a second cam member 5 movably mounted on the bed and engageable with said movable member near the end of the return movement acting to release said paper gripper, a keeper movably mounted on said bed and engageable with said second cam member and normally holding the second cam member in camming position, and a fixed member engageable with said keeper at the end of the return stroke of the bed acting to move said keeper out of engagement with the second cam member thereby releasing said paper gripper for regripping movement, said movable member acting upon said second cam member at the beginning of the printing movement to return it to camming position.

4. In a proof printing press having a rotatable horizontally mounted cylinder, a horizontal form bed movably mounted for reciprocation under said cylinder with means for moving said bed upon rotation of the cylinder, and paper gripping means lengthwise and at one side of the cylinder having a fixed bar at the periphery of the cylinder and radially movable rods with gripping heads at their outer ends for gripping paper between said heads and the outer side of the bar, a longitudinally movable member extending lengthwise axially of said cylinder and beyond it at one end, longitudinal movement of which in one direction moves said gripping heads outwardly from the bar, movable means mounted 10 against said projecting end of said axial member, operation of which in one direction moves said axial member to lift the gripping heads, a cam member secured near the outer end and at one side of the bed, projecting therefrom and movable therewith engageable with said last mentioned means on movement of the bed to its innermost position, acting to release a sheet of paper gripped by said gripping heads against said bar, and a second cam member movably 15 mounted on said bed near the opposite end thereof, engageable with said axial member to lift said gripping heads on outward movement of the bed near but short of its extreme outward position, keeper means for holding said second movable member against movement, and means on said bed acting to move said keeper means out of operative relation to said second cam member to release it for movement for return of the gripping heads to gripping position against said bar on completion of outward movement of said bed substantially to its extreme outward position.
